UNITED STATES PATENT OFFICE.

NESTER L. BROWN, OF OWENSBORO, KENTUCKY.

CONCRETE BURIAL-VAULT.

1,091,282.

Specification of Letters Patent.

Patented Mar. 24, 1914.

Application filed June 24, 1913. Serial No. 775,486.

To all whom it may concern:

Be it known that I, NESTER L. BROWN, a citizen of the United States, residing at Owensboro, in the county of Daviess and State of Kentucky, have invented a new and useful Concrete Burial-Vault, of which the following is a specification.

The present invention appertains to burial vaults, and aims to provide a novel and improved concrete vault to receive a casket or coffin.

One of the objects of the present invention is to provide a novel joint between the lid or cover and the box or receptacle, whereby the vault may be hermetically sealed after the casket or coffin has been inserted.

Another object of the present invention is to provide a novel and improved reinforcing frame for the body or receptacle.

A further object of the present invention is to provide a skeleton frame for reinforcing the body of the vault, which shall be comparatively simple, and inexpensive in construction, as well as convenient and efficient in its use, and the several parts of which may be readily built up in molding the body of the vault.

With the foregoing and other objects in view, which will be apparent as the nature of the invention is better understood, the present invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawing, wherein:

Figure 1 is a cross section of the vault, also illustrating the mold for forming the same. Fig. 2 is a fragmental side elevation of the vault, a portion thereof being broken away on the line 2—2 of Fig. 1. Fig. 3 is a fragmental elevation of the reinforcing frame. Fig. 4 is a perspective view of a fragmental portion of the reinforcing frame. Fig. 5 is a fragmental plan view of one corner of the vault.

In carrying out the invention, reference being had in detail to the drawing, there is provided a body or receptacle 1, molded

from concrete or other plastic material, and embodying the bottom 2, sides 3 and ends 4. The body or box 1 may be molded in various sizes or portions, as necessary, and is rectangular or oblong in outline.

A cover or lid 5 is provided for the body 1, the same being molded from concrete or equivalent material, and being preferably in the form of a slab convexed longitudinally and laterally.

A novel joint is provided between the lid 5 and the rim or upper edges of the body 1, the rim of the body 1, being provided with a continuous upper V-shaped groove 6. The outline of the lid 5 is only slightly larger than the interior dimensions or outline of the body 1, in order that the edges of the lid will slightly overlap the sides and ends of the body inside of the grooves 6. The rim or upper edges of the body are also provided with lips 7 along the outer edges of the grooves 6, and over-hanging the said grooves slightly. The lips 7 provide downwardly facing shoulders for locking the lid in position, as will be hereinafter described.

The lid 5 is provided with a reinforcement 8, preferably of expanded metal, or its equivalent, the reinforcement 8 being provided with the angle iron portions 9 extending along the side and end edges of the lid, with their elbows disposed downwardly. The angular members or extensions 9 are made to conform with the grooves 6, they being designed to seat snugly within the said grooves, and the outer flanges of the members 9 are free, in order that they may flex or bend so as to snap under the lips 7 when the lid is seated on the body. Thus, when the lid is placed in position, the outer or free flanges of the members 9 will snap under the lips 7, when the members 9 are seated in the respective grooves 6.

It will be evident that the lid 5 is not placed in final position, until the coffin or casket is inserted into the body 1, inasmuch as the lid cannot be removed after once being engaged to the body, without breaking the body, which would be objectionable. After the lid is placed upon the body, it will be apparent that there is provided a continuous groove or channel between the edges of the lid and the lips 7 and into this channel, there is poured cement or any other suitable sealing agent, preferably of a liquid or semi-liquid consistency. The sealing

material 10 in being poured into the channel between the lid 5 and the lips 7 will run into the angle members 9, and will fill in all crevices or spaces between the lid and body, so as to provide a perfectly hermetic joint, for excluding air or for preventing the ingress of the elements. The material 10 may be worked flush with the lid 5 and lips 7 so as to provide a neat appearance, it being noted that the sealing material 10 is adapted to run underneath the lips 7 so as to be locked against removal, without breaking the same.

The bottom 2 of the body 1 is provided with any suitable reinforcement 11, such as scrap wire, tin or the like.

The sides and ends of the body are provided with a novel reinforcing frame, as will be presently described. The skeleton frame for reinforcing the body embodies the corner uprights 12, which are preferably formed from angle iron, and which have their elbows disposed outwardly. A series of upstanding hooks 13 is attached to the inner face or side of each flange of the angle members 12 along its free edge, and a plurality of longitudinal strips 14 are supported by the respective hooks 13. The ends or terminals of the strips 14 are designed to lie flatly against the inner sides of the respective flanges of the members 12, the strips 14 being provided with lower notches 15 adjoining their ends to engage over the lower ends of the hooks, the strips 14 seating within the hooks to lock the strips 14 and angle members 12 together. Each of the strips 14 is provided with a series of out-struck straps or loops 16, and a plurality of vertical strips 17 are inserted through the respective loops 16 of the respective strips 14. The upper ends of the strips 17 are preferably hooked, as at 18, to engage over the uppermost strips 14 when the strips 17 are slid home through the loops. The edges of the strips 14 and 17 are preferably serrated or scalloped, in order that the strips may be securely locked or embedded within the concrete.

The skeleton frame facilitated the reinforcement of the body, during the molding operation.

The method of molding the body, is as follows:—The bottom 2 is first molded within the lower portion of a mold embodying a bottom 19, and collapsible side and end walls 20. The side and end walls 20 each comprise a plurality of hinged sections, in order that the said walls may be gradually built up as the concrete is poured into the mold. After the bottom 2 has been molded within the lowermost sections of the walls 20, it being understood that the reinforcement 11 is inserted within the concrete during the molding operation, the corner members 12 are placed in position, by forcing the

lower ends thereof into the corner portions of the bottom 2, so that the members 12 will be held in position. The strips 14 are then engaged to the corner members 12, after which the upright strips 17 are inserted downwardly through the respective loops 16 until the hooks 18 engage or lock over the uppermost strips 14. The lower ends of the strips 17 engage within the bottom 2, so as to lock the strips 14 in position. The walls of the mold are then built up, the concrete being poured in as the walls are built up, until the sides 3 and ends 4 are complete. The rim of the body is then worked to form the grooves 6 and lips 7 and after the concrete has set, a body is ready for use. It is to be understood that during the molding operation, a suitable core is placed within the mold, or on the bottom 2, after the bottom has set sufficiently to support the core. The core and mold are readily removable after the body has set, and inasmuch as they are of no particular moment with respect to the present invention, they need not be further illustrated or described in detail.

From the foregoing taken in connection with the drawing, the advantages or features of the present invention will be apparent to those versed in the art, it being noted that the objects have been carried out satisfactorily, and that the present invention provides a desirable container for the purposes described.

Having thus fully described the invention, what is claimed as new is:—

1. A burial vault embodying a body having upper grooves in its edges, and lips overhanging the grooves, a lid, and a reinforcement for the lid, having angular members extending along the side and end edges of the lid to seat in the said grooves, the outer flanges of the said members being flexible to snap under the said lips.

2. In a burial vault, a body including a bottom, sides and ends, and a reinforcing frame comprising angle iron corner members, each flange of each angle iron member having a series of hooks, horizontal strips having their terminals resting against the respective flanges of the angle iron members, and having notches in their lower edges adjoining their respective ends engaging with the hooks, each of the said strips having a series of loops struck therefrom, and upright strips inserted through the respective loops of the respective horizontal strips, the upper ends of the upright strips being hooked to engage over the uppermost horizontal strips, the lower ends of the angle iron members and upright strips being engaged to the bottom of the body.

3. In a burial vault, a body including a bottom, sides and ends, and a reinforcing frame comprising corner members, each having a series of hooks, horizontal strips hav-

ing their terminals engaging the respective hooks and each having a series of loops struck therefrom, and upright strips inserted through the respective loops, and the lower ends of the corner members and upright strips being engaged to the bottom of the body.

In testimony that I claim the foregoing as my own, I have hereto affixed my signature in the presence of two witnesses.

NESTER L. BROWN.
